CLAIM

The ornamental design for a mobile phone, as shown and described.

DESCRIPTION

FIG. 1 is a front perspective view of a mobile phone, showing a first embodiment of our new design;

FIG. 2 is a back perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof;

FIG. 8 is a left side view thereof;

FIG. 9 is a front perspective view of a mobile phone, showing a second embodiment of our new design;

FIG. 10 is a back perspective view thereof;

FIG. 11 is a front view thereof;

FIG. 12 is a rear view thereof;

FIG. 13 is a top view thereof;

FIG. 14 is a bottom view thereof;

FIG. 15 is a right side view thereof;

FIG. 16 is a left side view thereof;

FIG. 17 is a front perspective view of a mobile phone, showing a third embodiment of our new design;

FIG. 18 is a back perspective view thereof;

FIG. 19 is a front view thereof;

FIG. 20 is a rear view thereof;

FIG. 21 is a top view thereof;

FIG. 22 is a bottom view thereof;

FIG. 23 is a right side view thereof; and,

FIG. 24 is a left side view thereof.

The broken lines in drawings show portions of the mobile phone that form no part of the claimed design. The oblique line shading in the drawings shows a transparent, translucent and highly polished or reflective surface.

1 Claim, 18 Drawing Sheets
